UNITED STATES PATENT OFFICE.

MELVILLE CLARK, OF CHICAGO, ILLINOIS.

REED-ORGAN CASE.

SPECIFICATION forming part of Letters Patent No. 296,134, dated April 1, 1884.

Application filed June 12, 1883. (No model.)

To all whom it may concern:

Be it known that I, MELVILLE CLARK, a citizen of the United States of America, residing at Chicago, in the county of Cook and State 5 of Illinois, have invented certain new and useful Improvements in Reed-Organs, of which the following is a specification, reference being had therein to the accompanying drawings.

10 This invention relates to the construction of reed-organ cases; and it has for its object to so arrange a reed-organ case that, for repairs or cleaning, it can be readily opened to get at the interior or action.

15 My invention consists in providing reed-organ cases with a hinged upper half, and with a hinged lid in the back of the case, the parts being so arranged that access may be gained to the interior of the case, either by throwing 2c back the hinged upper half or by opening the rear hinged lid, or whereby the part may be entirely removed.

In the drawings, Figure 1 represents a rear elevation of an organ having my improvements; Fig. 2, a transverse vertical section of the same with the back lid partly opened; Fig. 3, a similar section with the upper part of the casing turned back, and Fig. 4 a plan view of the organ.

30 Corresponding letters in the several figures of the drawings designate like parts.

A denotes the body part of the casing, and B the top part that carries the music-shelves, and C the lid in the rear of the body part. 35 The top B is removably secured at its front corners upon the body part A by two screws, b, while the lid C is removably secured to the rear of the casing by four screws, c.

For turning the top B of the casing back, so as to expose the upper portions of the action, the screws b b are loosened, when such top can be swung to be suspended to the rear of the body A of the casing on the upper edge of lid C, while for getting to the rear of the action the top B of the casing remains intact 45 and the screws c c are loosened, when the lid C can be turned upward against the back of top B; or, by loosening the screws b and c, the top B and lid C are both disconnected from the body part of the organ and can be removed, when the entire action is exposed, for the purpose of tuning, repairing, and cleaning.

With this method of constructing organ-cases a great amount of time is saved, and the danger of misplacing any parts of the organ 55 is done away with, thus avoiding all the petty annoyances connected with taking the instrument apart, as is the case with the old way of building organs, while it facilitates the frequent cleaning of the action, that is very desirable in a reed-organ.

What I claim is—

A reed-organ case consisting of the lower or body part, A, the top or shelf part, B, and the lid C, such shelf part B and lid C being connected 65 by hinges a, and being detachably secured to the body part, respectively, by screws b and c, all substantially as and for the purpose set forth.

In testimony whereof I affix my signature in 70 presence of two witnesses.

MELVILLE CLARK.

Witnesses:

LOUIS NOLTING,
ADAM GEO. WHITE.
